UNITED STATES PATENT OFFICE.

ARTHUR W. SAVAGE, OF UTICA, NEW YORK, ASSIGNOR TO SAVAGE ARMS COMPANY, OF UTICA, NEW YORK.

FIREARM.

No. 8 0,517.

Specification of Letters Patent.

Patented Dec. 25, 1906.

Application filed May 20, 1901. Serial No. 61,025.

To all whom it may concern:

Be it known that I, ARTHUR W. SAVAGE, of Utica, in the county of Oneida and State of New York, have invented certain new and 5 useful Improvements in Firearms; and I do hereby declare that the following is a full, clear, and exact description of the invention, which will enable others skilled in the art to which it appertains to make and use the same, 10 reference being had to the accompanying drawings, and to the figures of reference marked thereon, which form part of this specification.

The object of my invention is to provide a 15 firearm particularly adapted for use with small loads in target and light sporting shooting and an arm which is known as a "take-down," whereby the total length may be decreased or the arm taken in two for convenience in carrying or packing and also providing ready and complete access to all 20 of the working parts for cleaning and inspecting and convenient removal, whether uninjured or damaged.

25 A further object is to provide an arm which, while attaining the above-stated results, is strong to resist the explosion and not weak and shaky on account of take-down or separation features and in which the separation as between the working parts is accomplished in a way not detrimentally effecting the strength and close working points of the construction.

Other minor and further objects of the invention will hereinafter appear.

35 Figure 1 shows in perspective the firearm from the left-hand side. Fig. 2 shows a right-hand elevation. Fig. 3 shows certain 40 of the working parts in their relative arrangement in the firearm in connection with the dotted outlines of the frame or receiver. Fig. 4 shows a top or plan view of the breech-bolt. Fig. 5 shows a side elevation of the same. Fig. 6 shows the opposite side elevation. Fig. 7 shows a bottom view. Fig. 8 shows a front end view of the breech-bolt. Fig. 9 shows a section taken on line C D of Fig. 6, with the parts to the right of the section-line. Fig. 10 shows in perspective the 45 part of the receiver or frame attached to the barrel in connection with certain parts of the mechanism located thereon. Fig. 11 shows in perspective and without the stock 50

the portion of the receiver or frame which is attached to the stock and in connection with the magazine in position with reference to this part. Fig. 12 shows the same as Fig. 10, with the movable parts in a different position and the magazine of the arm in its relative position with this part. Fig. 13 shows the same as Fig. 11, with the magazine removed and operative parts of the firearm in changed position. Fig. 14 is a longitudinal section of the magazine, showing several cartridges in position therein. Fig. 15 is a cross-section of a portion of the magazine on an enlarged scale from that shown in Fig. 14. Fig. 16 shows portions of the frame and mechanism partially in section and on an enlarged scale from that at which they are shown in previous figures. Fig. 17 shows a rear end view of the upper portion of the magazine. Figs. 18, 19, 20, 21, and 22 show the shell-ejector in connection with portions of the frame and mechanism and its mode of operation.

Referring to the reference-figures in a more particular description of the device, 1 indicates the barrel of the firearm, and 1^a the stock. The barrel is attached to the barrel 80 portion of the receiver or frame 2, and the stock portion 3 of the receiver or frame is attached to the stock 1^a—that is to say, it is provided with a pair of tangs 3^a and 3^b, which receive and are inlet into the end of 85 the stock—and the stock is secured thereto in the usual manner in this class of firearms. The barrel and stock portions of the frame are readily separable to permit access to the working parts of the arm and are secured together as follows: The forward end of the stock portion 3 is provided with a tang or tenon 4, adapted to be received in an undercut mortise 5 in the barrel portion, and the stock portion 3 is provided with a conical 90 dowel-pin 6, (which is the head of a screw hereinafter described,) adapted to engage in a suitable opening 7 in the barrel portion. A thumb-screw 8, provided with a suitable enlarged head whereby it may be readily operated, passes through the stock portion, and its screw-threaded end is adapted to engage in the screw-threaded opening 9 in the barrel portion of the receiver.

The breech-bolt 10 of the firearm is contained within the receiver, being entirely in-

closed by the walls of the receiver and held and guided on the sides by the walls of the receiver. The receiver construction is such that the breech-bolt 10 is firmly locked in operative position against lateral displacement when the receiver parts are secured together; but when the parts are separated and the breech-block is in its rearward position it is free to be laterally separated from its supporting parts and may be readily disengaged for purposes of inspection or cleaning without the necessity of unloosening or taking out any of the parts associated with it. One side of the bolt 10, which is somewhat enlarged to enable it so to do, is adapted, when the breech bolt is in firing position, to close the ejection-opening 11 in one of the walls of the receiver. The breech-bolt is provided with an angular slotted opening 12 in a wing, in which slot 20 there operates a stud 13, provided on the sliding bar 14. The bar 14 is received in a groove 15 in the inner face of the side wall of the barrel portion of the receiver and is adapted to be reciprocated backwardly and forwardly by means of the sliding handle 16, to which it extends and to which it is attached. The sliding handle is movable along the bar 14, secured beneath the barrel.

The breech-up shoulder of the breech-bolt 30 I have indicated by 18, and it is adapted to engage when in firing position with the recoil-shoulder 19 in the top wall of the receiver. This top wall is formed integral with the portion 2 of the receiver and is faced on the edge, which is shown in Figs. 10 and 12, to engage with the opposite wall, as found in the part 3. The forward end of the breech-bolt 10 is provided with a lip or projection 10^a, adapted to rest on the upper edge of the operating-bar 14, (which it may be here noted is of greater thickness than the depth of the groove 15,) so that a portion of it projects into the chamber of the receiver and forms a support for the breech-bolt 10. The breech-bolt 10 carries the firing-pin 20, which extends longitudinally through the bolt and is provided at its rear end with a head, between which head and the rear end of the bolt is interposed a light spring 21, operating to retract the firing-pin. The rear end of the firing-pin is adapted to be struck by the hammer 22, which is pivoted in the receiver or frame part attached to the stock on the screw or bolt which carries the head 6 heretofore referred to. The hammer 22 is operated by a thrust-bar 23, having a conical end which engages in a cavity in the rear side of the hammer 22 as to one end and slides freely through an opening in the stud or projection 24 on the lower tang as to its rear end and carries the coil-spring 25, interposed between the stud 24 and the collar 26, secured on the thrust-bar 23. The hammer 22 is provided with a notch on its pivotal end, in which is adapted to engage the nose of the

trigger 27. The trigger is mounted on a pivot in the frame.

On the rear end of the operating-bar 14 there is provided a stud or projection 28, the rear side of which is adapted to engage with the cam-face 22^a of the hammer and cock the hammer when the operating-bar is moved rearwardly. The forward side of the stud 28 is beveled off to adapt it to engage with the wing of the bolt and furnish an additional support for the rear end of the bolt when in firing position. The trigger is operated by the trigger-spring 29, secured on the inner side of the upper tang and the locking-bar 30. This locking-bar 30 rests at its lower end on the rear portion of the trigger and is held in position as to its lower end by a pin passing through the slotted opening 31 in the bar and through the frame. The upper end of the bar 30 is provided with a pin-like portion 32, passing through an opening in the sliding piece or plate 33, located on the top of the upper tang. The upper tang is provided with a slotted opening 34, which receives a projection on the under side of the plate or slide 33, and the slide is held in position by a pin passing through a slotted opening 35 and the tang of the receiver. The bar 30, at its upper end, is also provided with a shoulder adapted to receive the end of the trigger-spring 29, said shoulder being provided with a pair of notches in which the end of the trigger-spring engages and which serve to maintain the upper end of the bar 30 and the slide 33 in their positions of adjustment. The upper end of the bar 30 is also provided with a shoulder 36, adapted to engage with the under side of the upper tang at the rear end of the slide 34 when the parts are shifted into position to adapt it to do so.

It will be seen that the receiver and its associated parts are divided in such a manner that those elements—namely, the breech-block, its action-bar, and the parts co-operating therewith—which, generally speaking, appertains to the mechanism for handling the cartridge and resisting the explosion when the discharge of the firearm takes place and which naturally belong to one group of instrumentalities, are all combined and arranged upon the barrel part of the receiver, while the hammer and trigger mechanism and their associated parts appertaining, generally speaking, to the mechanism for causing the explosion are all arranged on the stock portion of the receiver. This division of the receiver and the working parts is most advantageous, as any defect in or looseness of the joint between the receiver parts, either from want of care in operating the securing means or from wear or otherwise, does not weaken the gun against resisting the explosion or endanger the operator when the explosion takes place, and, further, the grouping of the parts renders the separation and as-

sembling of the barrel and stock portions an easier matter.

The magazine is an elongated box 40, which as to its upper end is received in a recess in the frame through an opening in the bottom of the frame, this recess being formed between the two receiver parts, as will be clear from Figs. 10 to 13, inclusive, and as to its lower end fits against the forward portion of the trigger-guard 41. The magazine contains a follower 42, operated by a spring 43, and is adapted to receive a column of cartridges laying side by side, substantially as shown. The magazine is removable and is secured in position in the gun by the catch 44, which is pivoted in the frame, as shown, and is provided with a portion 44^a, extending into the opening inclosed by the trigger-guard in suitable position to be conveniently operated by the finger. The rear wall of the magazine is provided with a tooth 45, with which the said catch is adapted to engage in securing the magazine in position. The upper end of the magazine is open and is provided with a pair of inwardly-turned edges or lips 40^a, extending forward from the rear side of the magazine and adapted to engage the rear portion of the body and the head portion of the cartridge. The rear wall of the cartridge-case is provided with a cut-out or notch 40^b, somewhat smaller in size than the rear end of a cartridge, which recess is adapted to afford a passage for the projecting continuous rib 50 on the under side of the breech-bolt. This rib 50 is provided at its front end with a nose or projection 51, projecting in advance of the face end of the breech-bolt and adapted to strike the end of the cartridge close to its lower edge as the same is advanced through the upper end of the magazine. The ribs 50 serve to hold the cartridge down in the magazine when the breech-bolt is in its forward or firing position and also hold the cartridges down in the magazine during a large portion of the opening movement of the breech-bolt and until the shell, which is withdrawn from the barrel, is ejected. It will be seen that by forming this continuous rib 50 along the under side of the breech-bolt the cartridges will be held from play during the reciprocations of the breech-bolt, and they will only advance from the magazine when the breech-bolt is in its extreme rearward position, as shown in Fig. 16, so that all danger of upward movement of the cartridges into the path of the breech-bolt, or into such position that jamming might occur, is avoided.

The cartridge-extractor 60 is a spring-60 hook mounted in a recess in the top of the breech-bolt, having the hooked end projecting in advance of the face of the bolt. The extractor 60 has a special downwardly-projecting lip or extension 61, which enables the extractor the sooner to engage with the car-

tridge as it rises from the magazine, controlling its movements and eventually securing it with or connecting it to the bolt. On the opposite side of the face of the bolt from the extractor there is provided a pair of projections 10^a and 10^b, adapted to engage the side of the head of the cartridge opposite the extractor and prevent it escaping sidewise from the extractor. The ejector 70 is located at a suitable point in a recess in the wall of the receiver (in the stock portion of the receiver) and is pivoted therein at 71. The ejector is operated in one direction by the comparatively powerful spring 72, secured in a recess in the same wall of the receiver and at 75 its free end resting on the rear end of the ejector 70.

The ejector 70 is provided with an abrupt shoulder 70^a, adapted to engage the head of the cartridge in the operation of ejecting, 85 also with the projecting nose 70^b, also adapted to engage with the head of the cartridge in the operation of ejecting. The forward end of the breech-bolt is provided with a groove-like recess on the side adapted to receive the 90 ejector, and the bottom of this recess is formed on an incline, as indicated at 10^c, constituting a cam.

To prevent the gun from jarring or accidentally opening, there is provided in the 95 sliding bar 14 a notch 14^a, in which is adapted to engage, when the breech is closed, a shoulder 75^b on the detent 75. The detent 75 is pivotally mounted in the frame on the screw 8 and is operated by the spring 76. This 100 spring 76 also operates the magazine-catch 44. The detent 75 is provided with an upwardly-extending face or plate-like portion 75^a, adapted to prevent a cartridge or shell 105 getting into the working parts of the gun, to the rear thereof, when the magazine is removed.

The stock and barrel portions of the frame are preferably placed together when the magazine 40 is removed and secured by the thumb-screw 8. The magazine can then be readily inserted into the opening in the bottom of the frame provided therefor and when in position will be caught and secured by the catch 44. When removed, the magazine is 110 loaded by inserting the cartridges in the top one after the other and engaging them under the shoulders 40^a at the top of the magazine. The cartridges are forced into the magazine against the tension of the magazine-spring 115 43. When the magazine is inserted in the arm with the breech-bolt in its closed position, the uppermost cartridge engages on the under side of the rib 50 on the under side of the bolt, and the cartridges are forced down 120 somewhat into the magazine. When the magazine is inserted with the breech-bolt withdrawn from its firing position, the uppermost cartridge in the magazine takes a position in advance of the breech-bolt, as shown 125 130

particularly in Fig. 12. This is also the position of the parts after the breech-bolt is withdrawn when the magazine is inserted with the breech-bolt in its closed position. 5 Of course, without further particular description, it will be understood that the breech-bolt is operated by means of the sliding forearm 16 and the connecting-bar engaging with the bolt. Starting with the parts, so 10 far as they are shown in the relative position shown in Fig. 12, as the bolt is moved forward, the nose 51 passes through the notch 40^b in the upper end of the magazine and engages with the head of the cartridge below 15 its center and close to its lower edge. The pressure on the rear end of the cartridge, together with the friction on the lips 40^a on the top of the cartridge, operate to elevate the nose of the cartridge and direct it toward the 20 chamber in the barrel. As the rear end of the cartridge passes the forward end of the lips or shoulders 40^a of the magazine the rear end particularly rises under the action of the magazine-spring and the head of the shell is 25 immediately engaged by the depending lip 61 of the extractor. If at this point the motion of the breech-bolt should be reversed, the head of the shell will engage with the forward end of the shoulders 40^a of the magazine and block the backward movement of the bolt, or else the head of the cartridge will ride 30 up on the shoulders 40^a and the cartridge would be ejected in the regular way. It is quite important that after the cartridge 35 has been started to a material extent by the bolt of the magazine that a reversal of the movement of the bolt will not leave the started cartridge free and independent, so that the bolt can go back to pick up a second 40 cartridge from the magazine, and thereby produce a jam. In the regular movement of the bolt after engaging the cartridge as heretofore pointed out after the cartridge passes entirely out of the upper end of the magazine 45 it is forced into the barrel rising in front of the bolt, and the head being engaged between the extractor 60 and the projections 10^a and 10^b on the end of the bolt. When the cartridge is entirely in place in the chamber of the barrel, the shoulder 18 on the breech-bolt rises into engagement with the shoulder 19 on the frame, and the bolt is 50 locked ready for firing. The firing is accomplished by pulling the trigger 27, releasing the hammer 22, which strikes the rear end of the firing-pin 20, the forward end of which 55 engages the shell and explodes it.

When the bolt is in closed position, the detent 75 is engaged in the notch 14^a in the operating-bar 14, securing the bar and parts 60 against accidental opening or opening by a jar. The detent-catch is not a positive catch, but such a one that it requires some little force applied to the bar 14 to overcome 65 the catch.

In opening the gun, after firing or otherwise, the following operations take place: The rear end of the bolt is dropped down to disengage the breeched-up shoulders. As the bolt is drawn back, the projection 28 on the rear end of the operating-bar 14 engages with the cam-face 22^a on the hammer and proceeds to cock the hammer. The extractor 60, being engaged with the head of the cartridge, withdraws it from the barrel and moves it backward with the bolt. During this operation the cartridges in the magazine are held down by the rib 50 on the under side of the breech-bolt. 70 When the operation has proceeded far enough, one side of the head of the cartridge engages 75 with the abrupt shoulder 70^a on the ejector. To permit this to be done, the ejector is allowed to move into the path of the bolt and shell by the cut-away groove on the end of the bolt and the cam-bottom 10^c thereof. 80 As the cartridge comes back toward the ejector, one position is shown in Fig. 18 of the drawings. The position of the parts when the ejector has moved into the path of the bolt and shell and becomes engaged with 85 the shoulder is shown in Fig. 19. The continued backward movement of the bolt changes the position of the shell from that shown in Fig. 19 to that shown in Fig. 20, throwing the mouth end of the shell toward the ejection-opening 11. The further movement of the shell, as shown in Fig. 21, causes the side of the head in engagement with the ejector to slip off from the first shoulder onto the nose portion 70^b, and the swinging movement of 90 the muzzle of the shell is continued. At about this time, the extractor has lost its hold and the nose of the ejector catching the head of the shell in its final movement into the path of the bolt throws the shell out of 95 the opening. Of course all these movements are instantly performed; but the shell is effectually ejected to the side of the arm, tumbling end over end. When the bolt and 100 bar 14 have reached the limit of their backward movement, the hammer has been entirely thrown back and caught by the trigger 27, and the forward end of the breech-bolt will be retracted to the rear of the magazine and allow the cartridges to rise, so that 105 the forward one will take a position in front of the bolt, as heretofore described. The pivotal end of the hammer 22 and more properly the portion forward of the trigger-notch is made full and concentric with the pivot, so 110 that when the hammer is down the trigger will be held in its rear position. This causes the push-bar 30 of the trigger mechanism to be raised to its highest position, in which the end of the pin-like portion 32 is projected 115 above the plate 33, indicating the fact that the hammer is down. When the trigger is caught in the trigger-notch and the hammer is cocked, as shown in Fig. 3, the part 30 is in 120 its lowest position, as shown in Fig. 3. 125

When it is desired to lock the trigger, the plate or part 33 is shifted to the rear from the position in which it is shown in Fig. 3, thereby catching the shoulder 36 under the 5 upper tang of the receiver and locking the trigger. In shifting the upper end of the bar 30 by means of the plate 33 the shoulder on which the end of the trigger-spring 29 engages is shifted under the end of the spring, 10 and, as before stated, there are shallow notches or depressions provided in this shoulder, so that the spring may be engaged in either and secure the locking-bar 30 against accidental displacement. It will be observed 15 that the plate 33 is arranged on the firearm in convenient position to be operated by the thumb of the hand, which also operates the trigger.

It will be observed that the arm can be 20 loaded through the ejection-opening 11 with or without the magazine in position by turning it on its side, so as to bring this opening uppermost.

What I claim as new, and desire to secure 25 by Letters Patent, is—

1. In a firearm, the combination of a barrel, a stock, a receiver divided in a vertical plane into complementary separable parts, one of which is attached to the barrel and the 30 other to the stock, a breech-bolt and its operating mechanism arranged on and separable with the barrel portion of the receiver, hammer and trigger mechanism arranged on and separable with the stock portion of said receiver, and means for detachably securing the 35 parts of said receiver together, substantially as set forth.

2. In a firearm, the combination with a barrel of a stock, a receiver divided vertically and 40 longitudinally into separable complementary parts, one of which is attached to the barrel and the other of which is attached to the stock, the barrel part including the recoil-shoulder, a reciprocating breech-bolt arranged on the inner wall of the barrel portion 45 of said receiver, so as to be separable therewith without disengagement from the recoil-shoulder and yet laterally removable therefrom when the parts of the receiver are separated, and means for securing the two parts of 50 the receiver together so as to inclose and confine the said breech-bolt between the parts, substantially as set forth.

3. In a firearm, the combination of a barrel, a stock, a receiver divided vertically and longitudinally into two separable complementary parts, one of which is attached to the barrel and the other to the stock, means for securing the receiver parts together, and 55 a magazine removably mounted and secured between the separable parts of said receiver, substantially as set forth.

4. In a firearm, the combination of a barrel, a stock, a receiver divided vertically and 60 longitudinally into two separable parts, one

of which is secured to the barrel and the other of which is secured to the stock, means for detachably securing said receiver parts together, an ejector mounted on the inner face and separable with the stock portion of said receiver, and a reciprocating breech-bolt mounted on the inner face of and separable with the barrel portion of said receiver, said breech-bolt lying adjacent to and against the 70 said ejector, substantially as set forth. 75

5. In a firearm, the combination of a barrel, a stock, a receiver divided vertically and longitudinally into two separable complementary parts, one of the said receiver parts being attached to the barrel and forming a 80 confining and guiding wall for the breech-bolt at one side, the complementary receiver part being attached to the stock and forming a confining and guiding wall for the other side of the breech-bolt, a fixed recoil-shoulder 85 for the said breech-bolt formed on the barrel portion of the receiver, the breech-bolt mounted on and separable with the barrel portion of said receiver without disengagement from the breech-up shoulder, and 90 means for detachably securing the said receiver parts together to inclose and confine the breech-bolt, substantially as set forth.

6. In a firearm, the combination of a barrel, a stock, a receiver between said barrel 95 and stock divided longitudinally on a vertical plane into two separable complementary parts, one of said receiver parts being permanently attached to and carried by the barrel, the other part permanently attached to 100 and carried by the stock, the barrel part including the recoil-shoulder, a sliding action carried by and separable with the barrel portion of said receiver, a reciprocating breech-bolt connected with and separable with the 105 action-bar and barrel-receiver part, a hammer and trigger mechanism mounted on and carried by the stock portion of said receiver and separable therewith, and means for detachably securing the said receiver parts together 110 so as to inclose and confine the mechanism therebetween and in operative relation to each other, substantially as set forth.

7. In a firearm, the combination of a barrel, a stock, a receiver between said barrel 115 and stock divided longitudinally on a vertical plane into two separable complementary parts, one of which is carried by the barrel and includes the fixed recoil-shoulder, and the other of which is carried by the stock, an 120 action-bar mounted in a groove in the barrel portion of said receiver, a breech-bolt mounted on and separable with the barrel portion of the receiver and operatively connected with the action-bar and held in breeched-up 125 and engaging position with the breech-shoulder when separated, and means for securing the said receiver parts together, substantially as set forth.

8. In a firearm, the combination with a 130

6
barrel, of a stock, a receiver between said barrel and stock divided longitudinally on a vertical plane into two complementary parts, one of which parts is carried by the barrel and the other of which parts is carried by the stock, a sliding action-bar mounted in a groove in the wall of the barrel portion of said receiver, said action-bar being of greater thickness than the depth of the groove in which it moves, a breech-bolt operatively connected with said reciprocating action-bar, said breech-bolt resting upon the projecting upper edge of said action-bar, and means for detachably securing the said receiver parts together, substantially as set forth.

9. The combination in a firearm of the barrel, the stock and receiver divided vertically and longitudinally into two separable parts, one of which is attached rigidly and permanently to the barrel, and having a recoil-shoulder arranged on said part only, and the other part attached to the stock only, a sliding fore-arm mounted under the barrel, an operating-bar connected with the fore-arm and arranged in, supported by and longitudinally movable in a straight groove in the inner face of the barrel part of the receiver, a longitudinal movable breech-bolt having a rising and falling motion at its rear and to engage and disengage the recoil-shoulder connected directly with and supported against downward displacement by said operating-bar supported in said groove, substantially as set forth.

35 10. In a firearm, the combination of a barrel, a stock, a receiver between said barrel and stock divided into two separable parts on a vertical longitudinal plane, one of which receiver parts is permanently attached to the barrel and the other receiver part permanently attached to the stock, a recoil-shoulder on the barrel portion of said receiver, a breech-bolt inclosed and confined between the receiver parts when the gun is in assembled condition and separable with the barrel part without disengagement from the recoil-shoulder, a magazine, a magazine-recess between said receiver parts to receive the magazine and hold it in operative relation to the breech-bolt and other mechanism when the receiver parts are in assembled condition, and means for securing the said receiver parts together, and means for operating the breech-bolt, substantially as set forth.

55 11. The combination in a firearm of the barrel and barrel portion, of a receiver consisting in part of the side wall 2 and the top 2^a, said two parts arranged to receive and provide a recoil-shoulder for the breech-bolt, and a way or groove 15, the reciprocating operating-bar received in said groove or way 15 and carrying a projecting pin, the breech-bolt having in its rear end a cam-opening receiving said pin on the operating-bar and also supported at its front end on said operat-

ing-bar, the stock portion of the frame or receiver consisting in part of a side wall and a bottom wall and carrying the hammer and trigger mechanism, means for securing the two parts of the receiver together, and a magazine adapted to be inserted from the under side of the frame, substantially as set forth.

12. In a firearm, the combination with a barrel of a stock, a vertical and longitudinally-divided receiver between said barrel and stock, one of said receiver parts being attached permanently to the barrel and the other permanently to the stock, a recoil-shoulder on the barrel portion of said receiver, breech-bolt-operating mechanism mounted on and separable with the barrel portion of the receiver, a breech-bolt inclosed and confined between the separable receiver parts and separable with the barrel part without disconnection from its operating mechanism or the recoil-shoulder, trigger and hammer mechanism mounted on and separable with the stock portion of receiver, and means for securing the said receiver parts together, substantially as set forth.

13. The combination in a firearm of the barrel, the stock, the receiver divided vertically and longitudinally into two separable parts, one of which is attached to the barrel only and the other attached to the stock only, the barrel part including the recoil-shoulder, the breech-bolt and its operating mechanism mounted in and upon and separable with said barrel part of receiver and when engaged with the recoil-shoulder, and a hammer and trigger mechanism mounted in, on and separable with said stock part of receiver, a magazine-opening formed in part in each of said receiver parts, a removable box-magazine inserted in said receiver from the under side, and means for detachably securing said two parts of receiver firmly together, substantially as set forth.

14. The combination in a firearm of the barrel, the barrel portion of frame or receiver consisting in the main of the walls 2 and the top 2^a, and having the ejection-opening 11, the groove 15 and the recoil-shoulder 19, the reciprocating operating-bar received in said groove 15 and provided with an external handle for manipulating the same, and having the stud or projection 13 and the stud or projection 28, the breech-bolt carrying the firing-pin and the extractor, and having the recoil-shoulder 18 fitting in and operating upon said barrel portion of receiver, and having the cam-opening in its rear portion engaging with said stud or projection 13 and adapted to be engaged and locked by said stud 28, the stock portion of the receiver adapted to engage and set onto the barrel portion of receiver, and means for securing the two parts together, the said stock portion of receiver carrying the trigger, hammer and ejector.

mechanism, a removable box-magazine, an opening into the receiver from the under side adapted to receive said box-magazine, said opening being formed partially in each portion of the receiver, and means for securing said box-magazine in position in the receiver, substantially as set forth.

In witness whereof I have affixed my signature, in presence of two witnesses, this 14th day of May, 1901.

ARTHUR W. SAVAGE.
